DEVICE FOR FACILITATING DARNING

Arnold Arthur Storey, Leicester, England

Application August 7, 1934, Serial No. 738,871
In Great Britain September 1, 1933

5 Claims. (Cl. 223—100)

This invention relates to devices for use in the operation of darning and it concerns in particular those of the kind consisting of a holder over which the portion of the stocking, sock or other article to be darned is stretched to expose the hole.

The object of the invention is to improve holders of the kind concerned whereby the darning operation is facilitated and a neat darn can be made without skill or the exercise of care such as was heretofore necessary.

According to the invention there is provided in, on or for a darning holder of the kind concerned a part having open guides (for example channels or grooves) said part being adapted when the holder is in use to present its open guides under the hole to be darned so that they may serve to guide or position the darning needle across from one side of the hole to the other.

The invention is more particularly characterized in that the guiding channels or grooves are separated by walls or partitions upon the upper edges of which the bars of yarn of the first series are supported after completion of the series and the changing of the position of the work support, so as to facilitate the formation of the second series by interweaving of the bars of yarn of both series.

I will now describe, with reference to the accompanying drawing, a practical form and construction of darning holder constituting a convenient example of my invention.

In the drawing,

Figure 1 is a perspective view of the holder.

Figure 2 is a vertical sectional elevation of the holder in its normal condition.

Figure 3 is a vertical sectional elevation of the holder with the inner head or top lowered.

Figure 4 is a plan of the holder.

Figure 5 is a perspective view of the holder in use in one position, and

Figure 6 is a perspective view of the holder in use in another position.

Referring to the drawing, in this example, the holder body 1 is of mushroom shape and made of wood or other suitable material e. g. "Vulcanite," "Bakelite" or the like. The top 2 of the body has a central circular recess 3, and a stem 4 (which serves as the handle) bored centrally throughout its length. For part of its length extending from the bottom of the recess the said stem has a counterbore 5 which terminates in a shoulder 6.

The needle guiding part in the holder is preferably made of aluminium, but it may be made of other material like the holder, and comprises

a circular head 7 domed on the top side 8 and having on its underside a shank 9 extending rigidly and centrally therefrom. The said head and shank may be integral with each other but the shank is preferably screwed into a central boss 10 on the underside of the head 7 as shown in Figure 2. The domed top 8 of the head has cut or otherwise formed across it a series of parallel open channels or grooves 11 equally spaced. These may, for instance, consist of saw cuts. The uncut portions or ribs 12 of the top of the head stand up between the channels or grooves as walls. The head 7 may be cast or moulded in this form instead of being sawcut. The head is flat on its underside around the boss 10 and the channels or grooves are cut or formed to a depth uniform with the underside of the head, but as the top of the head is domed the channels or grooves 11 at the centre of the head are naturally deeper than those near the edge, as shown in Figure 3.

The circular recess 3 is of such diameter as to leave a narrow marginal portion 13 of the top 2 surrounding it this portion being rounded as shown. The inner channelled head 7 fits comfortably within the recess 3 and the latter is of sufficient depth to enable the said inner head to sink or be withdrawn into the top 2 as shown in Figure 3.

The shank 9 extends through the holder stem 4 and is slidable axially therein to move the head 7 up and down in the recess 3. Surrounding the shank on the head 7 is a compression spring 14 which is housed in the counterbore 5 and bears at one end against the shoulder 6 and at the other end against the underside of the boss 10. The spring tends to keep the head 7 raised in the recess as shown in Figure 2. The shank 9 projects through the lower end of the body stem 4 and has screwed upon it a collar, knob or handle 15 on the inner face of which nearest the end of the body stem is a peg or other projection 16. The lower end of the body stem which opposes the inner face just mentioned is formed with notches 17 there being four of these formations 45 disposed at an angle of 90° apart.

The said peg or other projection 16 and notches 17 constitute locking means and the action is as follows:—The spring tends to press the head 7 out of the recess 3 but this action is limited by contact of the collar, knob or handle with the adjacent end of the stem as shown in Figures 1 and 2. In normal position (Figures 1 and 2) the inner channelled head is held up in the recess so that its domed top projects sufficiently to 55

be available for use in the manner hereinafter described. When the parts are in this position the peg or projection 16 on the face of the collar, knob or handle 15 is located in one of the notches 5 in the stem 4 and thus prevents rotation of the shank 9 in the latter. To turn the channelled head 7 within the holder body 2 it is first necessary to pull the shank 9 down or outwards against the action of the spring to withdraw the peg or 10 projection 16 from the notch in which it is situated. This is done by means of the collar, knob or handle 15 and the axial movement of the latter within the holder body 1 thus imparted withdraws the channelled head 7 into the recess 3 as 15 shown in Figure 3. When the shank 9 has been pulled down or out sufficiently far to bring the peg or projection 16 out of the notch the shank 9 can be turned (compare Figures 2 and 3) within the holder thus turning the channelled head 20 within the recess. The lower end of the stem 4 is flat between the notches and during the turning of the shank the peg or projection 16 may be allowed to ride against the said flat end as shown in Figure 3, which prevents the shank 9 from receding under the spring influence. When, however, the peg or projection 16 comes to the next notch it drops into same thereby allowing the spring 14 to push the inner channelled head up 25 within the recess thus restoring it to normal position; the engagement of the peg or projection 16 with the next notch again locks the parts against relative rotation. It will thus be seen that the arrangement described ensures the channelled head 7 being withdrawn prior to and during turning thereof and also determines the position to which the said head is turned in the holder body. In other words it prevents turning 30 without withdrawal. The head 7 can be turned, when free, in either direction.

Referring to Figures 5 and 6, in using this device it is placed with the head 7 under the hole 18 to be darned and the fabric 19 is stretched over the top of the device and held by hand with or without a fastening such as an elastic band, tape or string placed over the fabric round the 40 handle. The channels or grooves 11 are thus exposed within the hole. The darning needle 20 is passed to and fro across the hole through the channels or grooves 11 as represented in Figure 5 to form the usual first series of bars 21 (warps) 45 which are accordingly located in the said channels or grooves, as represented by the few bars in Figure 5.

In the operation of darning as properly performed the darning needle after being withdrawn 50 to draw the yarn through one edge of the hole is re-inserted through the same edge at a point a little distance from the point of its withdrawal so as to space the bars of yarn. This spacing is facilitated by the use of the needle guiding 55 part 7 the channels or grooves 11 of which extend under the edges of the hole 18, the spacing being determined by using the guides one after another when inserting the needle, as represented in Figure 5. That is to say, when the yarn is 60 drawn through one edge of the hole at a point e. g. 22 coincident with a channel or groove 11 the needle is inserted through said edge, to form the next bar, e. g. at a point 23 coincident with the next channel or groove, and so on at opposite 65 sides of the hole.

The channels 11 are parallel to each other and extend across the part 7 in one direction as shown in Figure 4. The bars 21 when formed remain in their respective channels or grooves

until the head 7 is withdrawn and turned, as previously described, to free it from the bars 21, whereupon as shown in Figure 6, said bars become stretched or laid across the tops of the dividing walls 12, which therefore constitute supports for said bars, and the channels or grooves 11 are brought to right angular position for inserting the second series of bars. 5

As shown in Figure 6, being thus supported with channels or grooves underneath the bars of 10 the first series are in a favourable position to enable the darning needle guided by the channels or grooves 11 to be passed alternately under and over them to form the second series 24 (wefts) 15 interlaced with the first.

In Figure 6 the bars are shown relatively thin and well spaced for clearness, but, as will be understood, when fairly thick wool is used the bars 20 may practically touch when the work is removed from the holder so as to close the hole.

The domed top 8 projects upward slightly through the hole and thus provides better access to the channels 11 and to the bars of yarn when supported by said part.

The specific example described is particularly 25 useful since it enables full advantage to be taken of the needle guides for working in both directions without disturbing the set of the work on the holder after the formation of the first series of bars across the hole. This form of holder 30 enables the guides to be used in making the first series of bars and then while the work and holder are still held, the part with the guides can be turned to position the guides crosswise under the bars so that they can be used when 35 making the second series of bars interlaced with the first.

The withdrawable and rotatable part 7 of the holder may be removable from the holder body 40 (as for example by unscrewing the collar, knob or handle 15 from the shank) so as to be interchangeable with other similar parts having a different number of channels or grooves to the inch. In this way the device can be adapted for use for close or coarse darning according to 45 requirements.

Instead of cutting the channels or grooves in the needle guiding part or producing same by a moulding process, these may be produced by the insertion of blades or plates to form the dividing 50 walls or partitions.

The channels or grooves 11 are preferably distributed over the whole upper surface of the head 7 so as to present an adequate number of guides under the hole to be darned. 55

My invention includes within its ambit a part, having open guides as aforesaid, adapted for use by itself, for example it may be in the form of a disc, plate or like member, or for application to and use with a holder of the kind concerned in 60 which case it may, for instance, be in the form of a cap, cover or the like and be appropriate for use upon existing holders. My principal intention, however, is to incorporate the needle guiding part in a holder body such as 1, in which 65 case the said part may be either movable axially and rotatable as aforesaid or formed as an integral portion of the holder body, for instance the guide grooves or channels might be cut or otherwise formed in the top of the holder, or a part 70 having the guides and walls might be applied to the holder body such, for example, as by being inserted into the top or attached thereto.

What I claim then is:—

1. A device for facilitating darning comprising 75

a holder body, and a needle guiding part having a series of parallel walls of heights which diminish gradually from the center of the part to the edge and combined with the holder body in such a way that said part and body are capable of relative rotation and axial movement, whereby, when the device is in use with the needle guiding part under the hole to be darned, the spaces between the walls serve to guide the darning needle in forming the usual first series of bars of yarn forming warps and when the relative positions of the walls and work are changed so as to bring the walls at right angles to the warps, the walls support the warps upon their upper edges so as to facilitate the passage of the darning needle alternately under and over the warps while the spaces guide the needle in forming the second series of bars forming wefts.

2. A device for facilitating darning comprising a holder body, a needle guiding part having a series of parallel walls of heights which diminish gradually from the center of the part to the edge and rotatably combined with the holder body as well as being adapted to be withdrawn into the said body so as to enable the spaces between the walls to be used in one position for guiding the darning needle in forming the usual first series of bars of yarn forming warps, then withdrawn into the holder body to free said warps and then turned and projected to its normal position so as to bring the walls under the warps at right angles thereto so that the walls support the warps upon their upper edges so as to facilitate the passage of the darning needle alternately under and over the warps while the spaces guide the needle in forming the second series of bars forming wefts, and means for determining the rotational positions of the needle guiding part and locking same in said positions.

3. A device for facilitating darning comprising a holder body, a work supporting top, a needle guiding part with parallel walls of heights which diminish gradually from the center of the part to the edge and form between them spaces for guiding the darning needle during formation of the usual warp and weft bars of yarn, said part being rotatable and movable axially within the holder body, means operable exteriorly of the holder body to rotate the needle guiding part within the body while the work remains on the top for the purpose of bringing the walls under the warps at right angles thereto so that when the needle guiding part is again projected the walls support the warps upon their upper edges so as to facilitate the passage of the darning needle alternately under and over the warps

while the spaces guide the needle during formation of the wefts, means for determining the rotational positions of the needle guiding part and locking same in said positions, and a spring acting in an axial direction for controlling the needle guiding part and ensuring engagement of the locking means.

4. A device for facilitating darning comprising a holder body consisting of a circular top with a central circular recess and a hollow stem counterbored for a portion of its length from the inner end and formed with notches spaced at 90° apart at its lower end, a needle guiding part consisting of a circular domed head with parallel yarn supporting walls which diminish in height from the center of the head to the edge and form between them spaces for guiding the darning needle during the formation of the usual warp and weft bars of yarn, a central shank screwed into the head, said head and shank fitting both rotatably and slidably in the circular recess and hollow stem respectively with the shank projecting from the lower end of the stem, a compression spring around the shank in the counterbored part of the stem for holding the head raised in the circular recess, a handle on the lower end of the shank for withdrawing the head into the recess against the spring action and turning same in the holder body, while the work remains on the top, for the purpose of bringing the walls under the warps at right angles thereto, so that when the head is again projected the walls support the warps, at different heights upon their upper edges so as to facilitate the passage of the darning needle alternately under and over the warps while the spaces guide the needle during the formation of the wefts, and a projection on the handle for engagement with the notched stem under the spring action, said projection and notches constituting locking means for determining the rotational positions of the needle guiding part and holding same in such positions.

5. A darning implement of the character described, comprising a casing and an encased last, the latter being provided with a series of parallel walls forming intervening channels constituting guides for the passage of the darning needle during the laying of the warp threads or yarns, and constituting supports for the latter above said channels while the woof threads or yarns are being laid, the said last being adjustable within the casing for the purpose of changing the position of the guiding and supporting means relatively to the work after the formation of the warps.

ARNOLD ARTHUR STOREY.
